DUAL BATHTUB CONTROL

Samuel John Stanton, Chicago, Ill.

Application February 28, 1938, Serial No. 193,039

4 Claims. (Cl. 4—196)

This invention is an improvement on my invention disclosed in my application for patent Serial No. 169,409 filed October 6, 1937. The primary feature of the present invention is a mechanical combination which makes possible the use of a simple discharge control for the tub and the use of one opening, within the tub, both as an inlet and an outlet for the bathtub bathing water.

Three major advantages result from this: One is the absence of obstructive inlet devices like faucets. Two is the absence of the conventional hole and plug from the floor wall in the tub. Three is the elimination of a complex mechanism which the conventional floor "pop-up" valve requires. Four is the effect of a "neater-job."

Other effects, advantages and purposes of this invention will become patent as the disclosure of it proceeds in the following detailed description, in connection with the accompanying drawings which, together with the text, are made a part of this specification, terminating in the set of conventional claims.

In the drawings as figures:

Figure 1 is a perspective view of a bathing tub with the front wall thereof broken in part.

Figure 2 is a fragmentary vertical cross sectional view of Fig. 1.

Figure 3 is a cross section taken on the line 3—3 of Figure 2.

Figure 4 is a fragmentary cross section on the line 4—4 of Fig. 2.

Figure 5 is a fragmentary cross section on the line 5—5 of Fig. 2.

Figure 6 is an enlarged fragmentary sectional view of a part shown in Figure 2.

Figure 7 is a perspective view of another form of the present invention.

Figure 8 is a fragmentary sectional view longitudinally taken on Figure 7. It includes complementary equipment presumably invisible in Figure 7 by virtue of being imbedded in a building wall fragmentarily represented around the tub end in Figures 3 and 9.

Figure 9 is a cross section taken on the line 9—9 of Figure 8.

Figure 10 is a rear elevational view of Figure 7.

Figure 11 is a fragmentary sectional view of a modified form of valve lift and lowering means.

Figure 12 represents a fragmentary broken view of a tub end.

Figure 13 is a cross section taken on line 13—13 of Figure 12.

In the drawings particularized:

The numeral 10 points to a bathtub as a whole, which in general formation is like the conventional bathtub known to the art. It has a top portion, or rim, 11 confluent with upright walls 12 and 13 thereunder, which are integral with each other as well as with a floor wall 17 em-

braced between them. At the juncture of one of the upright walls and the said embraced floor wall is embodied an opening 14, which is the opening serving the dual purpose of inlet and outlet.

The numeral 28 indicates a water-tight chamber, back of the bathtub, having an opening 14 which coincides with the opening 14 of the bathtub. The numeral 27 indicates a drain pipe, one side thereof extending from or joined to the bottom wall of the tub, and another side thereof extending from or joined to the said water-tight chamber. The said chamber and the said drain pipe are so connected to each other as to form therethrough a continuous leak-proof channel, which channel in one part thereof is in confluent relationship with the opening 14 communicating therewith.

The numeral 25 indicates a valve sleeve—a tube threaded externally, smooth internally—fitted into the drain pipe under a plane of the bathtub floor and at the juncture of the drainpipe and the chamber superimposed thereon. The numeral 24 indicates a plug or valve fitting watertight into the seat 26, formed correspondingly within the valve sleeve 25. The numeral 23 indicates a stem extending from the plug 24 to an arm 20 at the stem top.

The arm 20, bifurcated, is a part of the combination more readily seen in the enlarged view thereof, in Figure 6, where 18 indicates a control handle, 19 a pivot over which the arm operates. The numeral 22 shows a pin through the stem 23, 24 a slot through the bifurcated arm 20—one fork being directly back of the exposed fork—the stem 23 being held by the pin 22 between the two forks of the arm 20.

Like in the invention disclosed in my above mentioned application, the bathing water for the tub is supplied through the mixing chamber 28 by and from the hot 30 and cold 31 supply pipes, entering the chamber near its top, from which mixing chamber the said water is deflected into the bathtub by the valve or plug 24 in its seat 26, the top of the chamber being watertightly closed.

An over supply of water in the tub flows out through the overflow opening or openings near the rim like that shown by numeral 15.

But unlike that of my previously mentioned application the final contents of the tub after a bath are drained off, not through a hole in the floor wall, but through the same opening which admits the water into the tub. This is made possible by raising the plug 24 or valve from and above its seat 26, whereupon a free passage into the drain pipe 27 is effected.

The numeral 16 indicates a grate situated back of the opening—or within the opening 14 in Figures 7, 8 and 9—this drain is provided to pre-

vent consequential solid substances from passing out into the drain.

The numeral 38 indicates a housing with a passage 29 therethrough. It is incorporated at the end of the tub, either on the side—see 20' in Figures 12 and 13—of the watertight mixing chamber 28 or in the back of it—as shown in Figures 2 and 4—to receive the overflow through openings 15 near the rim and direct the same to the drain pipe 27, for which purpose the passage 29 ends at and extends into an opening therefor into the channel of the drain pipe, at a plane preferably under the valve sleeve.

The numerals 32 and 33 indicate control valves for the supply pipes, 34 shows a cross pipe leading from the supply pipes to the faucet 35, which is intended to supply drinking water for the bather or hot and cold water for flushing the tub. The numeral 39 indicates an enlarged part of the housing 38, which is provided where a plurality of openings 15 are embodied near the rim. While the numeral 16 indicates a grate or screened plate, the numeral 16' indicates the openings in the said grate.

Sheet No. 2 of the herein incorporated drawings is included to show variations from the first described form of my invention. Corresponding parts are indicated by corresponding numbers, such numbers for convenience of distinction being primed or double primed in the second sheet.

One variation therein disclosed is in the arrangement of the grate. In the second model the combination inlet and outlet embodies an integrated grate. In the first model, the combination inlet and outlet, which is my preferred form thereof, is a wide graceful opening, protected by a grate situated back of the said opening, rather invisible under ordinary observation.

Another variation disclosed is a frictional device for the valve control. The valve stem 28' operates through a tight channel—in the disclosed model the channel is near the top. The knob 50 surmounting the stem replaces the handle 18 of the control device shown in Figure 2. A further variation is shown in Figure 11. Here a screw expedient replaces the frictional contacts of the control device shown in Figure 8.

The numeral 56 in Figure 11, corresponding to numeral 23' in Figure 8 is a valve stem. The numeral 57 indicates a threaded part of the stem, while the numeral 56 indicates a bushing internally screw threaded, and threaded correspondingly with the external threading on the stem at 57. The stem operates through the bushing, thread for thread. The numeral 55 indicates a knob on top of the stem 56. This knob rigidly fixed to or integral with the stem 56 is an expedient for operating the stem, to which valve 59—corresponding to 26'—is attached, through the bushing inserted in the tub rim indicated by the numeral 11.

Figures 12 and 13 represent a variation where in the channels 20' to direct the overflow are embodied on each side of the mixing chamber 28, which arrangement reduces the longitudinal requirements of space for the apparatus of the present invention.

The invention outlined herein is of course susceptible to various changes and modifications, the details here shown being merely for disclosure and not in limitation. The text herein is limited in description. The accompanying

drawings reveal only fundamentals. The right is therefore reserved to make such adaptations, developments and expansion as properly fall within the scope and purpose suggested by these combined text and drawings disclosures, summarized conventionally in the appended claims. 5

I claim:

1. In a cleansing water receptacle having a surrounding upright wall and a floor member, a common hot and cold water supply inlet in communication with the interior of said receptacle substantially at the junction of said wall and floor member and an over-flow outlet near the rim of said receptacle, a chamber, for mixing the supply, confluent with and above said supply inlet, a drain outlet below said supply inlet and said mixing chamber, a grating safeguard for said supply inlet and said drain outlet, a removable closure for said drain outlet below said grating, the removal of said closure draining said receptacle through said supply inlet past said grating, the said closure, in closure position contrived to hold the water fall from the chamber for deflection into the said bathtub, operating outside of said common supply inlet. 15

2. In a bathtub having an inner receptacle including a wall member, a floor member and a hot and cold water supply inlet adjacent said floor member, a chamber confluent with and above said supply inlet for mixing the supply, the wall member of said receptacle being continuous and impenetrable embodied as a solid common wall between said mixing chamber and said receptacle, a drain outlet below said supply inlet and said mixing chamber, a removable closure for said drain outlet, the removal of said closure draining said receptacle through said supply inlet, said closure in closed position deflecting the supply in said chamber into said receptacle. 30

3. In a bathtub having a surrounding wall member and a floor member, a common hot and cold water supply inlet in communication with the interior of said bathtub substantially at the junction of said wall and floor members, an overflow outlet near the rim of said wall member, a chamber confluent with and above said supply inlet for mixing said supply, a drain outlet below said supply inlet and said chamber, a removable closure for said drain outlet, the removal of said closure draining said bathtub through said inlet, the said closure, in closed position, deflecting said supply into said bathtub through said inlet. 45

4. In a receptacle for washing having a surrounding side wall, a floor member and a common hot and cold water supply inlet in communication with the interior of said receptacle, at the junction of said wall and floor member, a mixing chamber confluent with and above the said inlet, a drain outlet below said mixing chamber and said supply inlet, a liquid communication between the said mixing chamber, the said supply inlet and said drain outlet, closure means for the said drain outlet deflecting the inlet supply into said receptacle, and a rod extending through the receptacle rim operatively through said chamber for raising and lowering said closure means under the common inlet and outlet opening. 60

SAMUEL JOHN STANTON. 70
